UNITED STATES PATENT OFFICE.

SUSAN E. STEVENS, OF BOSTON, MASSACHUSETTS.

COMBINED SUSPENDERS AND STOCKING-SUPPORTER.

SPECIFICATION forming part of Letters Patent No. 375,216, dated December 20, 1887.

Application filed November 1, 1887. Serial No. 253,982. (No model.)

To all whom it may concern:

Be it known that I, SUSAN E. STEVENS, of Boston, in the county of Suffolk, State of Massachusetts, have invented a certain new and 5 useful Improvement in Combined Suspenders and Stocking-Supporters, of which the following is a description sufficiently full, clear, and exact to enable any person skilled in the art or science to which said invention appertains 10 to make and use the same, reference being had to the accompanying drawings, forming part of this specification, in which—

Figures 1, 2, and 3 are rear, front, and side elevations, respectively, showing my improvement in use.

Like letters and figures of reference indicate corresponding parts in the different figures of the drawings.

My invention relates to that class of stocking-supporters which are especially adapted for use by persons engaged in athletic exercises; and it consists in a novel construction and arrangement of parts, as hereinafter more fully set forth and claimed, the object being 25 to produce a more effective and otherwise desirable article of this character than is now in ordinary use.

The nature and operation of the improvement will be readily understood by all conversant with such matters from the following explanation.

In the drawings, A represents the suspenders, and B the supporter, considered as entireties. The suspenders are of the ordinary 35 form and construction, excepting that they are provided with an elastic stay or cross-brace, x, (see Fig. 1,) at the rear.

The supporter B consists of four straps, v z, each of the straps v being secured at m to the 40 front portion of one of the shoulder-straps t of the suspenders as shown in Figs. 2 and 3. The straps z are each secured at p to the rear portion of one of the shoulder-straps t of the suspenders, as shown in Figs. 1 and 3. The 45 straps v z cross each other under the arm of

the wearer and are secured together at b. The lower ends of the straps v z are provided with metallic rings i, to which are respectively secured elastic tapes k, their free ends h being folded back and secured by buckles l, 50 fastened to said tapes, thereby forming adjustable loops, to which are attached metallic catches g, adapted to grasp and hold the top of the stocking.

It will be seen that in use the strap z passes 55 from the rear of the suspenders A under the arm of the wearer, and its tape k across the front of the thigh, its clasp g being secured to the top of the stocking at the inner side of the knee. The strap v passes from the front of 60 the suspenders under the arm of the wearer, and its tape c down over the rear of the thigh, its clasp g being attached to the top of the stocking at the outer side of the knee. By arranging the straps v z as described a continuous strain is exerted on the stocking, thus 65 holding it in proper position while the wearer assumes any attitude desired.

By supplying the suspenders A with the stay x the straps t are prevented from becoming separated or displaced by the strain exerted thereon by the supporter B.

Having thus explained my invention, what I claim is—

1. In combined suspenders and stocking-supporter, the suspender-straps t, in combination with the crossed supporter-straps v z, provided with the elastic tapes k, and having the clasps g, substantially as set forth.

2. In combined suspenders and stocking-supporter, the suspender-straps t, provided with the brace x, in combination with the crossed supporter-straps v z, provided with elastic tapes k, having the clasps g, and adjusting buckle l, substantially as described.

SUSAN E. STEVENS.
